(57) **CLAIM**

The ornamental design for a roofing membrane seam plate, as shown and described.

DESCRIPTION

FIG. 1 is a top perspective view of a roofing membrane seam plate showing inventors' new design;
FIG. 2 is a top plan view;
FIG. 3 is a bottom plan view;
FIG. 4 is a rear elevational view;
FIG. 5 is a front elevational view;
FIG. 6 is a right side elevational view; and,
FIG. 7 is a left side elevational view.
